UNITED STATES PATENT OFFICE.

LEVI W. LOMBARD AND NATHANIEL LOMBARD, OF BOSTON, MASSACHUSETTS.

BRAIDING-MACHINE.

SPECIFICATION forming part of Letters Patent No. 429,136, dated June 3, 1890.

Application filed December 21, 1887. Serial No. 258,603. (No model.)

To all whom it may concern:-

Be it known that we, LEVI W. LOMBARD and NATHANIEL LOMBARD, citizens of the United States, residing at Boston, in the county of Suffolk and State of Massachusetts, have invented certain new and useful Improvements in Braiding-Machines; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to braiding-machines, particularly that class employed to produce a round solid braid or one having a continuous solid core, as occurs in covering wire with insulating material, and in which a series of bobbins or spools carrying yarn or thread are caused to traverse about a central point, or that where the braid or cord is being formed.

The object of our invention is to produce a braiding-machine which will be capable of forming braid very much more rapidly than has hitherto been accomplished by the present class of machines, wherein the thread-carrying bobbins or spools have themselves been traversed, and where the wear and tear of the machine have been great and the speed slow, due to this method of intermittently moving and bringing to rest the spools carrying the thread. To illustrate the state of the art in this respect we would name the patent of Charles E. Barnes, October 5, 1880, No. 232,920.

To the end above stated our invention consists in the construction and combination of parts hereinafter particularly set forth and claimed.

The drawings accompanying this specification represent, in Figure 1, a general plan of a braiding-machine embodying our invention. Fig. 2 is a diametrical vertical sectional elevation on line $x-x$ in Fig. 1. Fig. 3 is a plan of the carrier-plate with the race-plate carrier removed. Fig. 4 is a vertical central section on line $y-y$ in Fig. 1. Fig. 5 is a vertical sectional elevation of the race-plate carrier. Fig. 6 is a perspective view of the switch-bar. Fig. 7 is a rear view, and Fig. 8 a front

view, both in elevation, of one of the race-plates. Figs. 5, 6, 7, and 8 are all enlarged to more distinctly show details of construction, 55 as well as Fig. 9, which is a transverse section of the race-plate. Fig. 10 is an elevation of the eccentric-rod 17 and the eccentric a , the shaft 14 being shown in cross-section. Fig. 11 is an enlarged view in section showing the 60 relative arrangement of the carrier-plate, race-plate carrier, switch-bar, and race-plate, with the thread passing beneath the latter. Fig. 12 is a top view of the race-plate, showing the thread passing between the switch-bar and race-plate. Fig. 13 is a modified form 65 of the race-plate carrier. Fig. 14 represents a section transversely of the raceway, showing the switch-bar tilted and in the position indicated in Fig. 12. Fig. 15 is a detail view 70 of the pivotal connection between the thread-carrier and its operating-rod.

In the above drawings, 2 represents a casting in which is inserted a hollow vertical post 3, containing a tubular shaft 4, having an enlarged portion 5, with a beveled gear 6 firmly affixed upon it. Above and inclosing said shaft is fitted a sleeve-shaft 7. The lower end of the latter is furnished with a second beveled gear 8, of the same size and with the 75 same number of teeth as the one 6. At the upper extremity of the sleeve-shaft 7 is attached a hollow cone-shaped carrier-plate 9, the angle of inclination being forty-five degrees. Midway upon said sleeve-shaft and 80 between the top of the carrier-plate and the gear 8 is loosely mounted a reciprocating flanged hub 10.

Suitably supported upon the journal-bearings 12 13 is a horizontal shaft 14, having a 90 pinion 15, which intermeshes with the gears 6 8, while a pulley 16 on its outer extremity connects by belt or otherwise with some prime motor, whereby continuous rotation of said shaft is effected. In the rear of the pinion 95 15 is an eccentric a , which is also mounted on said shaft and operates an actuating-rod 17, the end of which is united with a pin 18, secured in the lower part of the flanged hub 10. Diametrically opposite is a second pin 100 19, which serves as a guide and plays in a vertical slot 20, formed in the post 21, secured upon the base 2.

Attached to the upper end of the tubular

shaft 4 we have secured a second hollow cone-shaped race-plate carrier, with the inner surface of the latter coinciding with the exterior surface of the carrier-plate. By the above arrangement of mechanism, as described, and presuming rotation of the shaft 14 is in the direction indicated, the tubular shaft 4, gear 6, and race-plate carrier move (see Fig. 1) in direction of arrow 1, while gear 8, sleeve-shaft 7, and carrier-plate 9 revolve in direction of arrow 2, both at the same rate of speed. Moreover, the flanged hub 10, by means of the eccentric-rod 17 and pins 18 19, reciprocates freely upon the sleeve-shaft 7.

Having now described the main operating parts, we will now proceed to fully, clearly, and completely show the various other instrumentalities, their relations one with the other, as well as their *modus operandi*, wherefore by a cylindrical cord or braid is manufactured.

The carrier-plate 9 is a hollow shell or plate frusto-conical in shape by cross-section, and, as before premised, is securely fastened to the top of the sleeve-shaft 7. Externally and arranged around the lower edge of said plate 9 are a series of stationary spindles 66, 67, 68, and 69, having thread-carrying spools 23 24 25 26 mounted on them, these spindles being arranged in pairs diametrically opposite each other—that is to say, with a quarter of a circle of interval between spool and spool following the circumference of the circle. Tension-rods 27 are arranged in close proximity to them, one to each on the same side of the spool. On the opposite sides of the spools from said tension-rods are similarly arranged, but at a somewhat greater distance, the fixed hollow tubes or thread-guides 28, formed with diametrical slots 29 extending longitudinally thereof. These tubes are inserted through the substance of the material composing the carrier-plate and are adapted to receive thread-carriers 30. The latter consist each of a rod having an eye 31 in its free end, which plays in the thread-guide, its other end extending inwardly beneath the carrier-plate, and is united with a rocker-arm 32, pivoted to an ear 34, cast upon the interior of the carrier-plate and located about in line with the top of the reciprocating hub 10. Said rocker-arm is provided with a short nose or prong 35, engaging an annular groove 36 in the top flange of the hub. Hence upon rotation of the shaft 14 and reciprocation of the hub 10 rocking of the arms 32 is effected to produce right-line traverses of the thread-carriers 30. The latter upon their extreme inward thrust convey the threads 37 38 39 40 into four slots 41 42 43 45, which are cut radially in an annular rib 51, formed upon the carrier-plate. (See Fig. 2.)

All the above parts are fixed relatively to each other, but have common rotary motion imparted to them by the revolution of the carrier-plate 9, to which they are secured. Hence the threads 37 38 39 40 from the spools

23 24 25 26 will always reciprocate in and out of the slots 41 42 43 45, while the spools themselves revolve upon their axes as the threads 70 pass off from them.

Surmounting the carrier-plate and resting thereon is placed the race-plate carrier 46, similar in form to said plate 9, and with its lower portion thickened. (See Fig. 5.) Upon the lower edge of this plate 46 are pivotally secured a series of switch-bars 47. The race-plates are shown at 48, and consist of curved plates with two oppositely-disposed L-shaped ribs 49 50, longitudinally arranged, and by means of which the race-plates are retained upon the raceway. The latter consists of an annular rib 51, cast exteriorly of the carrier-plate and above the point of attachment of the thread-guides thereupon. In the upper face of this rib 51 is cut a continuous cam-groove 52, while two other grooves cut therein engage the ribs 49 50 of the race-plates. The race-plates are inserted by means of a removable plate 90 (see Fig. 14) cut from the annular rib 51. When the requisite number of race-plates have been mounted upon the rib, said plate 90 is restored to its proper position and secured by screws or otherwise. Thus it will be seen that the race-plates travel continuously upon the carrier-plate, but are given rotation in an opposite direction bodily by means of the race-plate carrier through the interconnecting agency of the switch-bars 47. The latter are pivoted tangentially to the lower edge of the race-plate carrier, (see Figs. 1 and 5,) with laterally-projecting roller-pins 53 set in the "forward" ends, so called, with relation to their rotation, and which, moreover, engage in the cam-groove 52. The latter imparts rocking motion to said switch-bars, and such movement is effected by the position and form of the cam-groove, which serves to depress the forward end of each switch-bar just prior to its arrival opposite a radial slot 41 42 43 45. Similarly and upon advance movement of the race-plates the rear end of said switch-bar is depressed and at the same point. Moreover said switch-bars are provided at each end with an ear or stud 54 56, respectively at the rear and forward ends thereof, and these alternately co-operate and engage in two depressions 57 58, cut in the race-plates. The rocking motion of the switch-bars before alluded to, and caused by the roller-pins 53 in their passage about the cam-groove 52, compels the studs 54 56 to alternately engage, respectively, in these depressions. Thus when one is disengaged the other is in engagement with the race-plate. Therefore the race-plate carrier is always directly connected with each race-plate, and the latter are forced to rotate in unison simultaneously and continuously, but oppositely to that of the carrier-plate upon which they travel.

Fig. 11 shows the switch-bar about horizontal, as in Fig. 5, with the thread beneath a race-plate. In Fig. 14 said switch-bar is in the position shown in Fig. 12, with its forward

end depressed, the stud 53 being then in the portion 67 of the cam-groove.

Tension-rods 59 are applied to the spools 60 61 62 63, which are mounted upon spindles 70 71 72 in parallelism with the angle of inclination of the periphery of the carrier-plate or at right angles to the spindles 66, 67, 68, and 69, affixed in the said plate. The object of this is to enable a large spool to be employed 10 on the race-plates, and at the same time cause a minimum travel outwardly of the thread-carriers, in order to pass over and clear the race-plates and spools, which necessarily must pass therebeneath in one step of the braiding process.

In Fig. 4 the shaft 4 is shown as tubular to permit the passage upwardly of a continuous wire 64, which, for instance, is to be covered with some insulating material. This wire is 20 provided with a constant feed device to advance it upward as the braiding is effected, while the threads are better positioned, laid in place, and brought compactly to the central point by means of a removable conical 25 cap 65, the central bore of which corresponds very closely to the size of the cord in process of being formed.

The operation of the various component parts, arranged substantially as hereinbefore 30 described and embodying the gist of our invention, and their relations one with the other, are as follows, presuming the shaft 14 is in active operation, and assuming that the flanged hub 10 is in a raised position, with the thread-carriers 30 at their extreme innermost 35 point, and with the threads from the spools 23 24 25 26 resting in the radial slots 41 42 43 45, and extending to a common central point—the wire 64. Furthermore, the race-plates 40 are advancing in the direction indicated by arrow 1 on the carrier-plate, which is traveling in the opposite direction, (see arrow 2,) and are just in the act of crossing said slots 41 42 43 45 in the annular rib 48, which 45 now contain the series of outer threads. At this particular moment the roller-pins 53 in the switch-bars are in the part 67 (see Fig. 3) of the cam-groove, which causes depression of the forward end of said switch-bars 50 and disengages that end from the race-plates, thereby forming an aperture between the latter and the switch-bars. When the forward ends of said switch-bars are depressed, the rear part is tilted up, and the race-plates 55 are now driven by the studs 54 engaging the depressions or slots 57. As the two plates—the carrier 9 and race-plate carrier 46—move oppositely, the resultant effect is to induce the threads from the spools 23 24 25 26 to pass 60 between the race-plates and the switch-bars as the latter rock, thus carrying said threads beneath the co-operating threads from the series of spools on the race-plates. As the rotation of the various parts proceeds, particularly the race-plates, one consequence of the 65 advance movement of the latter is to cause the roller-pins 53 on the switch-bars to travel

in the cam-groove 52 toward that portion marked 68, thereby gradually raising the forward end and simultaneously depressing the rear end of said switch-bars. At this time the forward stud 56 has engaged the cut 58, and the race-plates are still united with the race-plate carrier. When the pins 53 have reached the point 68 of the cam-groove, the rear ends of the switch-bars are depressed and the race-plates have passed over the threads from the spools on the carrier-plate. Immediately upon the completion of this step the eccentric-rod 17 actuates and depresses the flanged spool 10, which pulls downward the nose 35 of the rocker-arm 32. The latter thrusts the thread-carriers 30 simultaneously outwardly to their extreme positions in the thread-guides 28, the threads moving freely in the longitudinal slots 29. As a consequence of this movement, the threads from the spools 23 24 25 26 upon the carrier-plate are so elevated as to permit the next succeeding race-plate with its thread-carrying spools to pass 90 beneath said threads—that is, instancing that the thread from spool 25 passed through the switch and beneath the spool 61 on the race-plate, the raising of the thread coming from said spool 25 will allow the spool 61 and its race-plate to pass freely therebeneath, and the continuous and successive in-and-out movement required in braiding is thereby effected. Thus the reciprocations of the threads from the spools on the carrier-plate are timed 95 to pass into a slot in the annular rib and there remain at rest, while a race-plate and its switch-bar operate to allow its passage between them and beneath the thread-carrying spool on said race-plate. Moreover, said reciprocating threads are further timed to advance suddenly outwardly and there remain, while the next following race-plate and its thread-carrying spool pass beneath it. By this means an intertwining movement of the 100 several threads in the series is effected and a continuous braided cord, solid, or one formed about a continuous cord or wire, is produced.

A prominent feature, as before premised, in this machine is that the entire series of 115 thread-carrying spools have continuous rotary movement bodily, and the machine can be operated at high speed without any difficulty, since it is only necessary to properly time the passage of the spools on the race-plates past 120 the slots 41 42 43 45 in the annular rib on the carrier-plate in unison with the right-line reciprocations of the thread-carriers, which control the threads from the spools fixed on the carrier-plate.

In lieu of employing a race-plate carrier the periphery of which is an imperforate surface, a series of arms diverging from a central hub may be employed, in which event each of the series of switch-bars is pivotally 130 secured to the end of one of said arms. This construction is shown in Fig. 13, and is simply to render the weight of the machine less and reduce the cost.

What we claim is—

1. The combination, with a circular cone-shaped carrier-plate adapted to receive spools and rotating continuously in one direction, of 5 mechanism for causing such rotation, a frusto-conical race-plate carrier, a series of race-plates thereon adapted to receive thread-carrying spools, mechanism for causing said carrier to rotate continuously but concentrically 10 with said carrier-plate in an opposite direction, a series of thread-carriers secured to the carrier-plate, and which reciprocate in right lines transversely of the path of travel of the spools upon said carrier-plate, thereby to direct 15 the threads of this set of spools over and under the opposite and co-operating set of spools upon the race-plates, and mechanism for causing such reciprocation, substantially as stated.
- 20 2. In combination with two series of continuously but oppositely rotating thread-carrying spools arranged about a common center, mechanism for rotating one of said series, a frusto-conical carrier-plate for the other of 25 said series, provided with an annular rib having radial slots, mechanism for rotating said carrier-plate, the thread-carriers movable in right lines, and the flanged hub, means for moving said hub longitudinally, and oscillating arms whereby such motion is given to 30 said carriers to move the thread in said slots, substantially as set forth.
3. The combination, with a rotary cone-shaped carrier-plate having an annular rib 35 and adapted to carry concentric thread-bearing spools and mechanism for causing such rotation, the thread-carriers secured to said carrier-plate, their actuating sleeve-hub movable upon the shaft 7, said shaft, and means 40 for moving said sleeve-hub thereon, of the frusto-conical race-plate carrier moving oppositely above said carrier-plate, means for causing such motion, the series of race-plates which engage said annular rib moving there- 45 on, and the rocking switch-bars, whereby the race-plates are interconnected with and rotated by the race-plate carrier, substantially as and for purposes set forth.
4. A continuously-rotating carrier-plate 50 adapted to receive a series of spools and provided with a series of radial slots and an interior cam-groove, in combination with mechanism for rotating said carrier-plate, a series of thread-guides secured to said plate, a series 55 of thread-carriers which reciprocate the threads from said spools, oscillating arms which actuate said thread-carriers, a movable flanged hub engaging and actuating said arms, means for moving said hub, a race-plate, an oppositely-rotating carrier for said plate, means 60 for causing such rotation in said race-plate carrier, and tangential switch-bars attached to the latter carrier and rocked by said interior cam-groove, said race-plate being engaged and rotated by said switch-bars and 65 adapted to receive thread-bearing spools, substantially as set forth.
5. In braiding-machines, the combination, with a fixed post 3, tubular shaft 4 and its operating mechanism, as described, the frusto-conical carrier-plate 9, affixed to said shaft and adapted to receive a series of thread-bearing spools, and a series of tubular thread-guides affixed at right angles upon the cone periphery of the carrier-plate, of a flanged hub 10, the sleeve 7, on which it is loosely mounted, mechanism for moving said hub on 70 said sleeve, the rocker-arms 32, engaging said hub, and the thread-carriers reciprocated thereby within the tubular thread-guides 75 transversely of the rotation of the carrier-plate, as and for purposes specified.
6. In braiding-machines, the combination, with a continuously-rotating conical carrier-plate 9, having the cam-groove 52, annular rib 80 51, and a series of radial slots 41 42 43 45 cut therein, of mechanism for causing such rotation, the tubular thread-guides 28, slotted lengthwise and affixed at right angles to said carrier-plate and the sleeve-shaft 7 of the 85 shaft 4, the eccentric a, carried by said shaft, the rod 17, actuated by said eccentric, and the flanged hub 10, operated thereby to slide upon the sleeve 7, the rocker-arms 32, which engage said hub, and the thread-carriers 30, 90 reciprocating within the tubular thread-guides and actuated by the rocker-arms, substantially as stated.
7. In a braiding-machine, the race-plate carrier 46, provided with a series of tangentially-arranged switch-bars 47, with their pins 53, in combination with the carrier-plate 9, having an annular rib 51, radial slots 41 42 43 45, and cam-groove 52, the race-plate, and mechanism for rotating in opposite directions the 100 said race-plate carrier 46 and the carrier-plate 9, these parts 46 and 9 being frusto-conical in shape, concentrically arranged, and adapted to carry series of thread-bearing spools, and the said pins 53 being arranged to travel in 105 cam-groove 52, to cause rocking and alternate depression of each end of said switch-bars at the commencement and completion of the passage of the latter past the said slots 41 42 43 45, substantially as specified. 110
8. The carrier-plate 9, having an exterior annular rib 51, slotted radially at 41 42 43 45, the continuous cam-groove 52, and race-plate-retaining grooves, in combination with the race-plate carrier 46, the race-plates 48, which 115 travel upon the annular rib 51, the rocking tangentially-disposed switch-bars 47, uniting said race-plates with the race-plate carrier, and mechanism for rotating said carrier-plate 9 and race-plate carrier 46 in opposite directions, these parts 9 and 46 being frusto-conical in cross-section and adapted to carry series of thread-bearing spools, as and for purposes stated. 120
9. In a braiding-machine, a continuously-rotating carrier-plate 9, having a rib 51, formed with radial slots, and the cam-groove 52, the spindles 66, 67, 68, and 69 upon said plate, adapted to receive thread-bearing spools, and 130

mechanism which rotates said carrier-plates, the thread-carriers 30, the rocker-arms 32, reciprocating said thread-carriers, flanged hub 10, means for reciprocating said hub, a continuously-rotating race-plate carrier 46, means for rotating said race-plate carrier, a series of race-plates traveling upon the carrier-plate and rotated by the race-plate carrier, combined with a series of switch-bars 47, interconnecting said race-plates and switch-bar carrier, said race-plate having lugs 54 56, which engage the race-plates, and pins 53, which travel in the cam-groove 52, to cause rocking of the switch-bars, substantially for purposes specified.

10. The combination, with a continuously-rotary carrier-plate 9, furnished with spindles 66, 67, 68, and 69, set at right angles to its periphery and adapted to receive thread-bearing spools thereon, and means for causing such rotation, of the continuously reversely-rotating race-plate carrier 46, means for rotating said race-plate carrier, the series of race-plates 48, actuated thereby and furnished with a series of spindles 70 71 72 73, arranged at right angles to the spindles upon the carrier-plate and adapted to receive spools revolving axially thereon, means intermediate said carrier and said race-plate to actuate the latter, and mechanism for reciprocating the threads from the spools on the said carrier-plate, substantially as herein stated.

11. In braiding-machines, a carrier-plate 9, having an annular rib 51, formed with a cam-groove and radial slots, and a series of race-plates 48, with cuts 58 59, traveling upon said rib, combined with a race-plate carrier 46 and the interconnecting switch-bars 47, pivoted thereto and provided with lugs 54 56 and pins 53, said lugs alternately engaging said cuts 40 and the pins with the cam-groove to permit certain of the threads ingress beneath or egress from under the race-plates, for purposes specified.

12. In braiding-machines, a continuously-rotating carrier-plate 9, having an annular rib 51 and a cam-groove 52, and the series of race-plates which travel thereon, combined with mechanism for causing such rotation, a race-plate carrier 46, mechanism whereby it 50 actuates said race-plates reversely from the moving carrier-plate, and the tilting switch-bars 47, pivoted upon the race-plate carrier and engaging the race-plates front and rear, and provided with pins 53, which work in cam-groove 52, substantially for purposes herein set forth.

In testimony whereof we affix our signatures in presence of two witnesses.
